INVENTOR:

WILLIAM C. PARKER,
BY *Robert Burns*,
ATTORNEYS.

UNITED STATES PATENT OFFICE.

WILLIAM CHARLES PARKER, OF CHICAGO, ILLINOIS.

EMERGENCY LOCKING MECHANISM.

1,272,082.

Specification of Letters Patent. Patented July 9, 1918.

Application filed April 22, 1918. Serial No. 229,889.

To all whom it may concern:

Be it known that I, WILLIAM CHARLES PARKER, a subject of the King of Great Britain, and a resident of Chicago, in the county of Cook, State of Illinois, have invented certain new and useful Improvements in Emergency Locking Mechanism, of which the following is a specification.

This invention relates to means for locking from one or remote points, the revolving doors of bank or like buildings in case of attempted robbery or like occurrence, and has for its object:—

To provide a simple and efficient structural formation and association of parts, whereby the revolving doors of a building are locked against revolution and from a remote point or points such as a bank teller's cage, and in a positive and substantial manner, all as will hereinafter more fully appear.

In the accompanying drawing:

Figure 1, is a plan view of the revolute member of the present mechanism.

Fig. 2, is a section of the same on line 2—2, Fig. 1.

Fig. 3, is a plan view of the stationary member of the present mechanism.

Fig. 4, is a section of the same on line 30 4—4, Fig. 2.

Fig. 5, is a combined side and end elevation of the locking bolt or pin of the mechanism.

Fig. 6, is a combined side and end elevation of the operating bar of the mechanism.

Fig. 7 is a combined side and end elevation of the guide plate for the aforesaid operating bar.

Fig. 8, is a plan view of the assembled mechanism.

Fig. 9 is a side elevation of the same.

Fig. 10 is an end elevation of the same.

Like reference numerals indicate like parts in the several views.

Referring to the drawings, 1 designates the guide plate, 2 the operating bar, 3 the gravity latch bolt or pin, 4 the revolute member, and 5 the fixed member of the present emergency locking mechanism.

The guide plate 1 aforesaid, is secured to a carrying bracket or post 6 of the fixed member 5 and is provided with a guide slot 7 to receive and guide the free end of the operating bar 2, and the said guide slot is preferably inclined as shown, so that the

tendency of the operating bar 2 will be toward an inoperative position under the ordinary jarring of the building.

The latch bar 2 aforesaid, is pivoted to a lateral post 8 on the fixed member 5, with its free end in guiding engagement with the slot 7 of the guide plate 1 aforesaid, said bar 2 is provided with one or more holes or orifices 9 for the attachment of pull wires which extend to remote points in the building so that the bar 2 may be actuated by persons at such remote point or points. The scope of the present invention however, embraces an actuation of the operating bar 2 from a remote point by any usual and suitable intermediate mechanisms.

The latch bolt 3 aforesaid is of a cylindrical form and provided with an angular upper portion 10 adapted to rest upon and be supported by the guide plate 1 in a normal inoperative position.

11 designates a rod or bar forming an operative connection between the operating bar 2 and the angular upper end 10 of the latch bolt 3 aforesaid.

The revolute member 4 aforesaid is of a circular form preferably, and formed on its under surface with a series of flanges 12 adapted for fixed attachment to the four radially disposed door members of a revolving door structure. On its upper surface the member 4 is formed with a circular flange 13 providing a cylindrical socket for a similarly formed hub 14 of the fixed member 5 hereinafter described. In the portion of said member 4 intermediate of the flanges 12 and 13 above described, is formed a circular series of vertical holes or orifices 15 adapted for locking engagement with the lower end of the latch bolt 3 aforesaid.

The fixed or stationary member 5 aforesaid, is of a flat plate form and provided with screw holes adapting the same for fixed attachment to the stationary housing of a revolving door in a strong and substantial manner. On its lower surface the member 5 is formed with the cylindrical hub 14 aforesaid and which by its engagement in the cylindrical socket of the revolute member 4 is adapted to maintain the parts in rotative engagement in actual use. On its upper surface the member 5 is provided with a lateral post 8 and with the bracket or post 6 above described, and with a vertical guide hole or orifice 16 arranged in axial aline-

ment with the bolt holes 15 of the revoluble member 4 and adapted to receive and guide the latch bolt 3 in actual use.

In the operation of the present invention, 5 as the operating bar 2 receives pivotal movement from a remote point as above set forth, it moves away from the latch bolt 3 and through the connecting rod 11 imparts a turning movement to said latch bolt, to move 10 the angular upper end of said latch bolt from its bearing on the top of the guide plate 1. With such disengagement the latch bolt 3 moves down by gravity to engage in the next adjacent bolt orifice 15 of the revoluble member 4 to lock the same from any 15 further rotation, and thus attain a locking of the revolving door of the building until the latch bolt 3 is removed from the locking engagement just described. The unlatching 20 and resetting of the latch bolt 3 to the normal inoperative condition first described, is effected by hand through a suitably guarded passageway in the stationary housing of the revolving door, and arranged in any safe 25 and convenient manner which the judgment of the constructor may deem best.

Having thus fully described my said invention what I claim as new and desire to secure by Letters Patent, is:—

30 1. An emergency locking means for revolving doors, comprising a fixed member adapted for attachment to a door housing and having a support and guide for a latch bolt, a latch bolt associated with said support and guide, a revoluble member adapted for attachment to a revolving door and formed with a circular series of bolt holes 35 adapted for engagement with the latch bolt aforesaid, and means adapted for operation 40 from a remote point for releasing the latch bolt for a locking engagement, substantially as set forth.

2. An emergency locking means for revolving doors, comprising a fixed member 45 adapted for attachment to a door housing and having a support and guide for a latch bolt, a latch bolt associated with said support and guide, a revoluble member adapted for attachment to a revolving door and 50 formed with a circular series of bolt holes adapted for engagement with the latch bolt aforesaid, and a pivoted operating bar adapted for operation from a remote point and

having operative connection with the latch bolt to release the same for a locking engagement, substantially as set forth.

3. An emergency locking means for revolving doors, comprising a fixed member adapted for attachment to a door housing and having a support and guide for a latch bolt, a latch bolt having vertical movement in said fixed member and formed with an angular upper portion engaging the support aforesaid, a revoluble member adapted for attachment to a revolving door and formed with a circular series of bolt holes adapted for engagement with the latch bolt aforesaid, and means adapted for operation from a remote point for releasing the latch bolt for a locking engagement, substantially as set forth.

4. An emergency locking means for revolving doors, comprising a fixed member adapted for attachment to a door housing and having a support and guide for a latch bolt, a latch bolt having vertical movement in said fixed member and formed with an angular upper portion engaging the support aforesaid, a revoluble member adapted for attachment to a revolving door and formed with a circular series of bolt holes adapted for engagement with the latch bolt aforesaid, and a pivoted operating bar adapted for operation from a remote point and having operative connection with the latch bolt to release the same for a locking engagement substantially as set forth.

5. An emergency locking means for revolving doors, comprising a fixed member adapted for attachment to a door housing and having a support and guide for a latch bolt, a latch bolt associated with said support and guide, a revoluble member adapted for attachment to a revolving door and formed with a circular series of bolt holes adapted for engagement with the latch bolt aforesaid, a pivoted operating bar adapted for operative connection with the latch bolt to release the same for an operative engagement, and a guide plate for said operating bar formed with an inclined guide slot, substantially as set forth.

Signed at Chicago, Illinois, this 20th day of April, 1918.

WILLIAM CHARLES PARKER.
